United States Patent Office.

NICHOLAS S. VEDDER, OF TROY, AND TOBIAS S. HEISTER, OF LANSINGBURG,
NEW YORK, ASSIGNORS TO J. L. MOTT, OF NEW YORK CITY.

Design No. 4,054, dated May 17, 1870.

DESIGN FOR STOVE-PLATES.

The Schedule referred to in these Letters Patent and making part of the same.

To all whom it may concern:

Be it known that we, NICHOLAS S. VEDDER, of the city of Troy, in the county of Rensselaer and State of New York, and TOBIAS S. HEISTER, of Lansingburg, in said county and State, have jointly invented and produced a new and original Design for Stove-Plates, of which the following is a specification, reference being had to the accompanying photographs of two stove-plates, each having our said design.

The distinguishing feature of our said design is a representation of a cotton-bale, A, cast on and forming a part of a stove-plate, so as to present an appearance substantially the same as is shown in and by the aforesaid photographs and herein described.

In casting plates for cooking, heating, and fire-place stoves with our said design, we commonly have the cotton-bale A apparently rest on one of its sides or

ends, and with two, three, four, or more corrugated or plain cords or bands, b, around the bale, and with or without a representation of a plant or plants, c, or a tree, d, and with or without a supporting base, f, projecting laterally beyond the side or end of the cotton-bale.

What we claim as our invention or production, and desire to secure by Letters Patent, is—

A representation of a cotton-bale cast on and forming part of a stove-plate, substantially as herein described and shown.

NICHOLAS S. VEDDER.
TOBIAS S. HEISTER.
